UNITED STATES PATENT OFFICE.

JEREMIAH E. REEVES, OF CANAL DOVER, OHIO.

PAIR AND SHEET FURNACE.

SPECIFICATION forming part of Letters Patent No. 653,756, dated July 17, 1900.

Application filed November 20, 1899. Serial No. 737,639. (No model.)

To all whom it may concern:

Be it known that I, JEREMIAH E. REEVES, a citizen of the United States, residing at Canal Dover, in the county of Tuscarawas and State 5 of Ohio, have invented new and useful Improvements in Pair and Sheet Furnaces, of which the following is a specification.

My invention relates to improvements in combined pair and sheet furnaces; and it consists in the arrangement of parts so that the heat from one fire-chamber is conducted through the pair-furnace and thence to and through the sheet-furnace and returns to the under part of the pair-furnace and thence to 15 the stack and is controlled and regulated by one damper placed on top of the stack, thus simplifying the construction, reducing both the cost of construction and the operation, and economizing and utilizing all the heat, as 20 will be hereinafter more fully described and claimed.

In the accompanying drawings similar letters of reference refer to similar parts.

Figure 1 is a vertical longitudinal section. 25 Fig. 2 is a sectional plan view. Fig. 3 is a foundation plan view.

A represents the fire-chamber, which is located at one end of the furnace and may be of any desired form. I have shown it provided with the usual grate-bars and ash-pit; 30 but it may be adapted either to the use of coal, oil, or gas.

B represents the pair-furnace, supported upon an arch b, sprung from the division 35 walls or partitions b¹ and b² between the sheet-furnace and the pair-furnace and between the pair-furnace and fire-chamber, respectively. The bottom of the pair-furnace is provided with upwardly-extending parallel 40 ridges extending transversely through the furnace, forming a support for the pairs. The parallel ridges b³ are formed of brick set in edgewise and extend throughout the entire length of the pair-furnace. It will be 45 observed that the floor of the pair-furnace is located within a comparatively-short distance of the top or roof covering C of the furnace, which causes the heated gases from the fire-chamber to pass through the pairs which may 50 be placed in the furnace and at the same time permits of the construction of the chamber D under the floor of the pair-furnace, which

communicates with the stack E by means of the opening e in chamber D, through which the heated gases pass on their way to the 55 stack, thus heating the under part or floor of the pair-furnace. The division-walls b¹ and b² terminate short of the roof, leaving the apertures or openings b⁴ and b⁵. The roof of the sheet-furnace is slightly elevated above that 60 of the pair-furnace and fire-chamber, and the floor F of the sheet-furnace is formed substantially the same way as that of the pair-furnace, excepting that the upwardly-extending parallel ridges or bars b³, upon which the 65 sheets rest, extend longitudinally through the furnace. On the forward end of the sheet-furnace and upon either side thereof there are provided recessed flues G, which communicate with the flues H under the floor of the 70 sheet-furnace. Both the pair and sheet furnaces and likewise the fire-chamber are provided with the usual form of doorways or openings J, and the furnace has the usual buck-stays for holding the casing thereof together and to the furnaces. The foundation 75 I may be built of concrete or brick.

In operation the fire is started in the fire-chamber and the damper on the stack opened, when the heat passes up and into the pair-furnace and thence into the sheet-furnace, 80 and by means of the recessed flues is thence conducted down to the flues underneath the sheet-furnace, which communicates with the chamber under the pair-furnace, and thence 85 into the stack, utilizing by the means thus employed all the heat and keeping all the parts of the furnace heated.

It will be observed that by this form of construction the number of attendants necessary 90 to operate the furnace is reduced, there being no dampers intervening between the various parts of the furnace requiring the services of an employee for their operation, and the fire from one fire-chamber furnishes the heat for 95 both furnaces, thus reducing the expense of operating the furnace, and having but one damper located on the top of the stack operated by the sheet-heater, thus preventing the pair-heater from overheating and sealing the 100 pairs in the pair-furnace and from sealing the sheets in the sheet-furnace, which frequently occurs in furnaces having a series of dampers operated by different employees. It will also

be observed that in furnaces of this construction the large item of expense and annoyance caused by replacing warped and burned-out dampers in use in furnaces of other types is obviated and that the flues all being constructed within the body of the furnace are more easily and more cheaply constructed and are at the same time more readily cleaned and repaired.

Having thus fully described my invention, what I desire to claim and secure by Letters Patent is—

The combination in a reheating-furnace, of a fire-chamber, an elevated pair-chamber communicating therewith, an elevated sheet-chamber directly communicating with the

pair-chamber, the floor of the sheet-heating chamber downwardly inclined toward and terminating adjacent to the pair - heating chamber, a return-flue underneath and parallel to the floors of the sheet and pair chambers, and of a width equal thereto, and communicating with a stack at the side of the pair-chamber, substantially as described and for the purpose set forth.

In testimony whereof I have hereunto set my hand in the presence of two subscribing witnesses.

JEREMIAH E. REEVES.
